UNITED STATES PATENT OFFICE.

JOHN W. ROBERTS, OF CLEVELAND, OHIO, ASSIGNOR TO THE ROBERTS TINWARE COMPANY, OF SAME PLACE.

CAN-SEAMING MACHINE.

SPECIFICATION forming part of Letters Patent No. 521,895, dated June 26, 1894.

Application filed December 1, 1893. Serial No. 492,424. (No model.)

To all whom it may concern:

Be it known that I, JOHN W. ROBERTS, a citizen of the United States, residing at Cleveland, in the county of Cuyahoga, State of Ohio, have invented certain new and useful Improvements in Can-Seaming Machines, of which the following, with the accompanying drawings, is a specification.

My invention relates to improvements in machines for seaming the heads upon the body of tin or othersheet metal cans by means of a double seam, and particularly to that class of machines in which the can is held stationary while having the heads seamed thereon in order that heads may be put upon filled packages.

The object of my invention is to simplify the construction of such can seaming machines with a view of increasing their facility 20 of operation, cheapen their construction, and to give them the greatest possible wearing life.

My invention consists in the particular construction, arrangement, and combination of the parts herein illustrated and described. Reference is here made to the claims for a 25 specific definition of my present invention.

In the drawings which form a part of this specification, Figure 1 is a side elevation of my machine. Fig. 2 is a front elevation of the 30 same. Fig. 3 is a plan on the sectional line $x\ x$ of Fig. 1. Fig. 4 illustrates a section on the line $y\ y$ of Fig. 1. Fig. 4^a is a section on the line $a\ a$ of Fig. 4. Fig. 5 illustrates an enlarged detail of the cam and pinion which 35 elevates the chucks or can carrier disks of the intermittent rotary carrier frame. Fig. 6 illustrates an enlarged plan detail of the can carrier chuck-lock, and Fig. 7 illustrates an enlarged front elevation of the same. Fig. 8 illustrates a section through a chuck and can carrier disk of the can carrier frame enlarged; and Fig. 8^a is an enlarged central section through the can gripping disk that holds the 40 upper end of the can. Figs. 9, 10, 11 and 12 are enlarged figures which illustrate different 45 positions of the irregular cone and seaming rollers in their operation upon a can. Fig. 12^a is a cross-section of Fig. 12 on the line $z\ z$. Fig. 13 is an enlarged plan of one of the 50 seaming rollers, and Fig. 14 is a central cross-section of the same. Fig. 15 is an enlarged

plan of one of the seaming rollers, and Fig. 16 is a central cross-section of the same. Fig. 1^a is an enlarged view illustrating the form of the parts of the can prepared to be operated 55 upon by my improved machine. Fig. 1^b is an enlarged view illustrating the first step in the operation of the machine. Fig. 9^a is an enlarged view illustrating the second step in the operation of the machine. Fig. 10^a is an enlarged view illustrating the third step in the 60 operation of the machine. Fig. 11^a is an enlarged view illustrating the fourth and complete operation of the machine upon a can.

The parts of cans, that is, the bodies and 65 ends of cans, are prepared by any suitable means to be operated upon by my machine. A broken section of a part of a can is illustrated by Fig. 1^a, which shows the form of the body and of the ends of cans as prepared 70 ready to be operated upon by my improved seaming machine. The cylindrical body, 43, has formed thereon upon each of its ends an outwardly projecting flange, 43'; and the ends, 42, have formed thereon the upwardly 75 projecting flange 42'', the horizontal surface 42'', and the downwardly projecting flange 42'. The parts are put together to be operated upon as illustrated by the broken sectional figure, Fig. 1^a. 80

In the several figures of the drawings, 1 represents a standard, which, together with the lateral projections 2, 3, 4 and 5, and the extensions 1' and 5', constitute the main frame of the machine which supports the operative seaming mechanism of the machine, while the frame 6 supports the can carrier mechanism.

7 is a standard having a journal box, 7', at its top, in which rotates the horizontal shaft 90 8 that is journaled in the standard 1, as illustrated by Fig. 1. At the outer ends of the lateral projections 2 and 3 are boxes or journals, 2' and 3', in which rotates a vertical shaft, 10. To the lower end of the vertical 95 shaft 10 is fixed a miter gear 11 which meshes with the miter gear 9 that is fixed upon the outer end of the horizontal shaft 8. A horizontal shaft is carried in the journals 1'' and 5'' at the top of the extensions 1' and 5', and a drive-pulley, 12, is fixed upon said shaft between the journals 1'' and 5''. To the outer 100

end of the shaft that is carried in the journals 1" and 5" is fixed a beveled gear, 13, which meshes with a beveled gear, 14, that is fixed to the upper end of the vertical shaft 15. At the outer end of the lateral projection 5 is a journal 5", which journal 5" is preferably made of considerable length for carrying the vertical shaft 15. There is fixed upon the vertical shaft 15, below the journal 5", a ring, 15", to prevent vertical movement of the shaft 15. Upon said shaft 15, above the journal 5", is a beveled gear, 16, having a boss 16', which meshes with a beveled gear 17 that is fixed upon the inner end of the shaft that is carried in the journals 1" and 5". Upon the lower end of the vertical shaft 15 is a gripping disk, which disk consists of the disk or plate 18 having a boss 18', into which boss there is a bore into which enters a shank, 19, formed upon the lower end of the vertical shaft 15. Around said shank there is formed a groove, 19'. A pin, 18", passes through a bore horizontally through the boss 18', said pin 18" fitting into the groove 19' of the shank 19. This construction of the holding plate or disk 18, boss 18', and shank 19 allows the shaft 15 to rotate while the gripping disk or holder 18 remains stationary, and the pin 18" prevents the holder 18 from becoming detached from the shaft 15 when there is no pressure upon the under side of the holder 18.

The detailed description so far given of my machine describes parts of the machine which are not new, and constitute no part of the present invention, except as they are combined with the parts that are herein described as new.

The particular seaming mechanism which 40 separately and in combination with other parts of the machine that are old constitutes the main part of my present invention is particularly described in the following paragraph. The other improvement, which relates to the manner of locking the spindle of 45 the can carrier disks when elevated, and which separately and in combination with other parts of the machine constitutes a part of my present invention, is hereinafter particularly described.

Upon the shaft 15 there is fixed a cross-bar, 20, which cross-bar rotates with the shaft 15. Lateral slots, 20' and 20", are made in said bar 20. At one end of the cross-bar 20 is pivoted a double swing lever, 21, by means of a pivot, 22, which passes through a slot, 20', which pivot, 22, has adjustment in the slot 20' and can be fixed at any point by means of the nut, 22', which is screwed upon one end of the pivot 22. A spring, 24, has its upper end attached to the upper end of the double swing lever 21 and its lower end attached to the washer 23. The object of this spring 24 is to keep the upper end of the double swing lever 21 thrown in as far as possible for the reasons hereinafter stated. At the opposite end of the cross-bar 20 is pivoted a like double swing

lever, 25, which double swing lever 25 has its upper arm longer than the upper arm of the double swing lever 21, while the lower arm of the double swing levers 25 and 21 are the same length, as illustrated in Fig. 1, and by Figs. 9, 10, 11 and 12. Said double swing lever 25 is pivoted in the slot 20" of the cross-bar 20 by means of a pivot, 26, having a nut, 26', for adjusting the pivot 26 in the slot 20", as illustrated. A spring, 27, has its upper end attached to the upper end of the double swing lever 25 and its lower end attached to the washer 26", as illustrated, to throw the upper end of the double swing lever 25 in as far as possible, for the purpose hereinafter stated.

The lower end of the double swing lever 25 has journaled thereon a seaming disk, 28, of 85 the form illustrated by Figs. 13 and 14, while the lower end of the double swing lever 21 has a seaming disk, 30, of the form illustrated by Figs. 15 and 16, journaled thereon.

While the form of the seaming disks is 90 seen in Figs. 9, 10, 11 and 12, their form is best seen illustrated by Figs. 13, 14, 15 and 16. The seaming disk that is carried by the lower end of the double swing lever 25 has a face that has a beveled edge, 28', and a groove 95 around its face which forms a bevel 29, leaving the upper side of the rim formed by the face 28' slightly grooved out, as seen at 28", while the top of said seamer is flat, as illustrated. The face of the seaming disk 30 100 that is journaled upon the lower end of the double swing lever 21 is but slightly beveled, as illustrated by Fig. 16. Upon the vertical shaft 15, above the cross-bar 20, there is loosely sleeved an irregular cone, 31. Through 105 the upper ends, 21' and 25' of the double swing levers 21 and 25, pass horizontally rods 32 and 33 which carry upon their inner ends friction rollers, 32' and 33', which are adapted to travel in engagement upon the varying 110 surfaces of the cone 31, as illustrated by Figs. 9, 10, 11 and 12. Said rods 32 and 33 have lateral adjustment by means of set-screws 21" and 25". From the upper side of the cone 31 project vertical rods, 32" and 32", which 115 vertical rods pass through a sleeve, 34, that is loosely mounted upon the shaft 15 above said irregular cone 31. Said vertical rods 32" and 32"" have vertical adjustment in the sleeve 34 and are fixed therein by means of 120 the set-screws 34" and 34". A rocking lever, 35, passes through an opening in the standard 1, which opening is indicated by the dotted lines 1''' in Fig. 1. The rocking lever 35 is pivoted between the lugs 36 and 36' that 125 project from the front of the standard 1. One end of said rocking lever 35 carries a yoke, 37, through the arms of which yoke pass studs, 38 and 38', that project from the ring 34' that fits in an annular groove of the sleeve 34, so 130 that by the tipping of the rocking lever 35 the sleeve 34 is raised and lowered and so raises and lowers the cone 31. As the sleeve 34 is supported by the yoke 37 through the

ring 34', the sleeve 34 may remain stationary and allow the shaft 15 to have rotary movement therein. The vertical rods 32" and 32'" will keep the sleeve 34 and the irregular cone 31 fixed with reference to each other, while both the sleeve 34 and the irregular cone 31 will allow the shaft 15 to turn in them, or the sleeve 34 and cone 31 may turn with the shaft 15, their rotary movement being controlled by friction. It is not essential that said sleeve 34 and irregular cone 31 rotate with the shaft 15, or that they have no rotary movement. If desired, the sleeve 34 and the irregular cone 31 may be made to turn simultaneously with the shaft 15 by means of a key, a feather, or other mechanism. I prefer to leave said sleeve 34 and irregular cone 31 free to turn or not to turn (as controlled by friction) with the shaft 15, as illustrated, as the wear of the cone 31 by the friction rollers 32' and 33' will be more evenly distributed around the cone than would be the case were the cone 31 made to rotate simultaneously with the shaft 15, in which construction the travel of the friction rollers 32' and 33' would always be in one line up and down the cone 31.

Upon the outer or back end of the rocking lever 35 is journaled a friction roller, 39, which friction roller travels over the cam 40 which is fixed upon the vertical shaft 10. Said cam 40 has upon its upper side the steps 40^a, 40^b, 40^c, 40^d, 40^e and 40^f, with the inclines 40^{a'}, 40^{b'}, 40^{c'}, 40^{d'}, 40^{e'}, and 40^{f'}. The friction roller 39 travels over said steps and inclines of the cam 40 and is held in engagement therewith by means of the spring, 41, which has its upper end attached to the outer end of the rocking lever 35 and its lower end secured to the standard 1 by means of the bolt 41', as illustrated. The steps and inclines of the cam 40 and the varying faces of the irregular cone 31 are made relatively to each other for the purpose of performing the different steps of seaming one of the ends upon a can body by bringing automatically the seaming disks 28 and 30 to operate alternately and conjointly upon a can and release both from the can upon the completion of the operation of seaming. When the friction roller 39 is upon the step 40^a of the cam 40, the irregular cone 31 is held in such position as that the seaming disks 28 and 30 are free of the can, as seen in Fig. 1.

In the drawings, the friction roller 39 is shown at the completion of its travel over the step 40^a of the cam 40 and about to start upon its travel up the incline 40^b. During the travel of the friction roller 39 over the step 40^a, the parts of the seaming device are in the position illustrated by Fig. 1. As the friction roller 39 travels up the incline 40^b of the cam 40, the friction roller 33' that is carried by the double swing lever 25 will come in contact with the lower edge of the inclined face 31^k of the irregular cone 31 and throw in the seaming disk 28 so as to turn in the flange

42' of the can top 42, as illustrated by Fig. 1^b. In this operation, the bevel 29 of the seaming disk 28 engages the edge of the flange 42', the lower edge of said flange passing down toward the groove 28" of the seaming disk 28. This position of the parts (not illustrated) is controlled by the step 40^b of the cam 40. The shaft 15 makes one revolution so as to make the seaming disk 28 travel once around the can with the friction roller 33' in contact with the lower part of the inclined face 31^k of the irregular cone 31 while the friction roller 39 travels over the step 40^b of the cam 40, to turn the flange 42' inwardly, as illustrated by Fig. 1^b, around the can. The friction roller 39 then travels up the incline 40^c of the cam 40 to the step 40^c, which brings the parts of the seaming device to the position illustrated by Fig. 9. In this position, (Fig. 9) which is the second step in the operation upon the can, the friction roller 33' is in engagement with the upper part of the inclined face 31^k of the irregular cone 31 while the friction roller 32' is in engagement with the lower part of the inclined face 31^l of the irregular cone 31, in which position the seaming disk 30 is still free of the can. The turning of the grooved seaming disk 28 against the can while the parts are in the position illustrated by Fig. 9, bends the flanges 42' and 43' to the position illustrated by Fig. 9^a. When the seaming device shall have made one-half a revolution in the position indicated by Fig. 9, during the travel of the friction roller 39 over the step 40^c of the cam 40, the travel of the friction roller 39 up the incline 40^d to the step 40^d brings the parts of the seaming device to the position indicated by Fig. 10 with the friction roller 33' against the vertical face 31^l and the friction roller 32' against the upper part 31^l of the irregular cone 31. The travel of the seaming disk 28 against the can bends the flanges 42' and 43' to the position shown by Fig. 9^a. In order to save time, the seaming disk 30 is brought into contact with the bent flanges 42' and 43' upon a half revolution on the step 40^d. The operation with the parts in position shown by Fig. 10 bends the flanges 42' and 43' of a can to the angle shown by Fig. 10^a. The travel of the friction roller 39 up the incline 40^e to the step 40^e of the cam 40 brings the parts of the seamer to the position shown by Fig. 11 with the friction roller 33' on the reduced inclined face 31^m of the irregular cone 31 to free the disk 28 from the can, and the friction roller 32' upon the enlarged vertical face 31^t of the irregular cone 31 to make the seaming disk 30 flatten the flanges 42' and 43' down upon the can body 43 and upon each other to complete the double seam, as illustrated by Fig. 11^a.

The operation of the several movements of the seaming device will be clear by associating the travel of the friction roller 39 over the step 40^a with the can parts as shown by Fig. 1^a, as they are put into the machine and gripped between the can carrier disks 49 and

the gripping disk 18; the first movement of the seamer, which is during the travel of the friction roller 39 over the step 40^b, bends the flange 42' to the angle shown by Fig. 1^b; the 5 second movement of the seamer, during the travel of the friction roller 39 over the step 40^c, brings the parts to the position illustrated by Fig. 9 and bends the flanges 42' and 43' of the can body and top to the angle 10 shown by Fig. 9^a; the third movement of the seamer, during the travel of the friction roller 39 over the step 40^d, brings the parts to the position illustrated by Fig. 10 and bends the flanges 42' and 43' of the can body and top to 15 the angle shown by Fig. 10^a; the fourth movement of the seamer, during the travel of the friction roller 39 over the step 40^e, brings the parts to the position illustrated by Fig. 11 and bends the flanges 42' and 43' of the can 20 body and top to the angle shown by Fig. 11^a and completes the double seam. The travel of the friction roller 39 over the step 40^f brings the friction roller 32' opposite the deep groove 31^a and the friction roller 33' free of 25 the irregular cone 31 so that the parts are in the position shown by Fig. 12 to let the completed can pass out. The return of the friction roller 39 to the step 40^a of the cam 40 returns the parts of the seamer to the position 30 shown by Fig. 1 ready to repeat the operation described.

The object of the springs 24 and 27 is to spread the seaming disks 28 and 30 to make them clear the can upon the completion of 35 the operation of seaming, as shown by Fig. 12.

In the following paragraph I describe the intermittent rotary can carrier with its chucks or disks, and the means employed for elevating the disks of the can carrier to grip the 40 can. Said parts of the machine constitute no part of my present invention, except as they are combined with the parts hereinbefore and hereinafter described as new.

The vertical shaft 44, stands in a journal 45 block 45, passes through a journal 6' of the frame 6, and has keyed upon its upper end a can carrier frame 46. Said frame consists of a circular band or rim having spokes or arms terminating in a central hub, as illustrated in the plan Fig. 3. Upon the vertical shaft 44 is fixed a drive-gear, 47, as seen by Figs. 1 and 2. Upon the inner end of the horizontal shaft 8 is fixed a mutilated bevelled gear, 48, which meshes with the gear 47. 50 The size of said gears 47 and 48 and the number of teeth upon the mutilated gear 48 and upon the gear 47 must so correspond to each other as that each revolution of the shaft 8 will rotate the can carrier table, 46, far enough 55 to bring successively the several can carrier disks, 49, under the gripping disk or pad 18. The shaft 15, carrying the upper gripping disk 18, is above the plane of the orbit of the can carrier disks 49. Said disks 49 have spindles, 50, which project through boxes or bearings, 46', formed around the carrier frame, as illustrated by Fig. 8, and have vertical move-

ment in said bearings 46', but have no rotary movement therein. Rotary movement of the spindles 50 and the can carrier disks 49 may 70 be prevented by making said spindles square and letting them pass through a square socket, or by the means illustrated, which consists in a pin, 51', projecting from the lower end of the spindle 50, the pin 51' projecting between the bars 52, 52', as illustrated by Figs. 1, 2 and 8. Upon the shaft 8, below the orbit of the spindles 50, is a cam 53. At the outer end of the lateral arm 4 of the main frame is a box, 4', through which a plunger, 80 54, works vertically, said plunger having upon its lower end a friction roller, 55, which travels over the face of the cam 53. The cam 53 is so placed upon the shaft 8 as that with each intermittent rotary movement of the 85 can carrier 46 as it brings successively the can carrier disks 49 vertically under the can gripping disk 18, said cam 53 forces up the plunger 54 so as to raise the spindle 50 and the can carrier disk 49 to grip between the 90 can carrier disk 49 and the can gripping disk 18 a can, as illustrated by Fig. 1.

The miter gears 9 and 11 make the shaft 8 revolve correspondingly with the vertical shaft 10, while the gears 14 and 13 and 17 and 16 are so made with reference to each other as that the shaft 15 carrying the can seaming device makes nine revolutions while the shaft 10, having thereon the cam 40, makes one revolution; and the rotary can carrier frame 100 46 rotates from one can carrier disk 49 to the successive can carrier disks 49' with one revolution of the shaft 8, one revolution of the shaft 10 and nine revolutions of the shaft 15. The vertical shaft 15 may be geared to a higher 105 or a lower relative speed than stated, if desired; but that given is preferable.

The parts of my machine described in the following paragraph are new, and separately and in combination with other parts of the 110 machine constitute a part of my present invention.

Figs. 6 and 7 illustrate a chuck-locking device which I employ for locking the chucks or spindles 50 while they are elevated by the 115 plunger 54 to grip a can to be operated upon. A lock-frame, 56, having an upper arm, 56', and a lower arm, 56'', is made to reciprocate back and forth as described in this paragraph. Said lock-frame 56 rests with its lower arm 120 56'' in slide-ways upon the top of the journal 4', and the plunger 54 passes vertically through the opening 56''' of the lower arm 56''. Said opening 56''' is elongated so as to allow the lock-frame 56 to reciprocate back 125 and forth. A horizontal bar, 57, is attached to the back end of the frame 56, and passes through the standard 1, as illustrated by Figs. 1 and 3, and has upon its back end a hook, 57'. Upon the vertical shaft 10 is fixed a 130 disk, 58, having a vertical pin, 58', which with each revolution of the shaft 10 comes in engagement with the inside of the hook 57' of the bar 57, which forms a catch, and throws

the lock-frame back from the position illustrated to free its grip upon the spindle 50. The lock 56 is withdrawn from the spindle 50 as the intermittent rotary can carrier table 5 is about to be moved forward by the mated pinion 48 to the next succeeding can carrier disk 49'. When the intermittent rotary can carrier frame 46 shall have been moved forward to bring the succeeding can carrier disk below the can gripping disk 18, the pin, 58', by the rotation of the shaft 10, becomes disengaged from the hook 57', and the spring 59, which is interposed between the frame 56 and the standard 1, throws said lock forward to engage the spindle 50' of the succeeding carrier disk, and lock the same, by frictional contact therewith as illustrated. This locking device is to make more rigid and firm the spindles 50 and can carrier disks 20 49 while a can is gripped between a can carrier disk 49 and the gripping disk 18 to be seamed.

My improvement is adjustable for seaming cans of various sizes by the vertical adjustment of the shaft 15 through the bevel gear 16, the adjustment of the irregular cone 31 upon the shaft 15 by the set-screws 34", and the lateral adjustment of the bars 32 and 33 by means of the set-screws 21" and 25".

30 The construction and operation of my improved machine for seaming the ends upon cans, have now been fully described. It is only necessary to state that the parts of the cans having been prepared as already described, 35 an operator takes said parts and puts them together and sets them upon the can carrier disks 49, and as the cans are completed after being operated upon, the cans are removed from the opposite side of the machine.

40 It will be seen that by my improved machine tin packages may be filled after having one end seamed thereon and the opposite end put upon the filled package. As the package is held perfectly stationary during 45 the operation of seaming, there is no shaking, splashing, or spilling of contents, and a perfectly solid double seam is formed around the end joints of the can or package.

What I claim as my invention, and desire 50 to secure by Letters Patent, is—

1. The combination of an irregular cone, a double swing lever, and a seaming disk carried by the double swing lever, substantially as illustrated and described.

55 2. An irregular cone, a double swing lever, a seaming disk carried by the lower end of the lever and a friction roller carried by the upper end of the lever, substantially as illustrated and described.

60 3. The combination of a vertical shaft, an irregular cone upon the vertical shaft and having movement thereon, a cross-bar fixed upon the vertical shaft, double swing levers pivoted to the cross-bar, and seaming disks 65 carried by the double swing levers, substantially as illustrated and described.

4. A vertical shaft, an irregular cone upon

the vertical shaft and having movement thereon, a cross-bar fixed upon the vertical shaft, slots laterally through the cross-bar near its 70 ends, double swing levers pivoted in the slots of the cross-bar, and seaming disks carried by the double swing levers, substantially as illustrated and described.

5. The combination of a vertical shaft, an 75 irregular cone upon the vertical shaft and having movement thereon, a cross-bar fixed to the vertical shaft, double swing levers pivoted to the cross-bar, seaming disks carried by the double swing levers, a cam having a series of 80 steps and inclines, and intermediate connection between the cam and the irregular cone whereby the irregular cone is lowered and raised upon the vertical shaft by the rotation of the cam, substantially as illustrated and 85 described.

6. The combination of a vertical shaft, an 90 irregular cone upon the vertical shaft, a cross-bar fixed to the vertical shaft, slots laterally through the cross-bar near its ends, double 95 swing levers pivoted in the slots of the cross-bar, seaming disks carried by the double swing levers, a cam having a series of steps and inclines, and intermediate connection between the cam and the irregular cone where- 95 by the irregular cone is lowered and raised upon the vertical shaft by the rotation of the cam, substantially as illustrated and de- scribed.

7. The combination of a vertical shaft, an 100 irregular cone upon the vertical shaft, a cross-bar fixed to the vertical shaft, double swing levers pivoted to the cross-bar, seaming disks carried by the double swing levers, a sleeve upon the vertical shaft above the irregular 105 cone, any suitable connection between said sleeve and the irregular cone, a rocking bar having connection at one end with said sleeve and its opposite end being operated by a cam having a series of steps and inclines, substan- 110 tially as illustrated and described.

8. The combination, in a can seaming ma- 115 chine, of a lock for the spindles of the can carrier disks consisting of a lock-frame having two arms, the upper arm being shorter than the lower arm, the lower arm having a slot through it, a horizontal bar having one end attached to the lock-frame and the opposite end provided with a hook, a rotating trip to engage said hook to withdraw the frame, 120 and a spring to return the lock-frame upon the release of the hook from engagement with the rotating trip, substantially as illus- 115 trated and described.

9. The combination, in a can seaming ma- 125 chine, of a vertical shaft carrying a can car- rier frame having an intermittent rotary movement, can carrier disks having spindles journaled around said frame, a plunger below the orbit of the spindles, a cam below the 130 plunger adapted to raise the spindles as the spindles successively come over the plunger in their travel at the end of each intermit- tent movement of the can carrier frame, a

vertical shaft above the orbit of the can carrier disks, said shaft carrying on its lower end a gripping disk, an irregular cone upon the vertical shaft carrying the gripping disk, a 5 cross-bar attached to said vertical shaft, double swing levers pivoted to said cross-bar, a vertical shaft having thereon a cam provided with steps and inclines, intermediate connection between said cam and the irregular cone 10 whereby the cone is lowered and raised by the rotation of the cam having a series of steps and inclines, substantially as illustrated and described.

10. The combination, in a can seaming machine, of a vertical shaft having fixed thereon a can carrier frame, can carrier disks having spindles journaled around the can carrier frame, a drive-gear fixed upon the vertical shaft of the can carrier frame, a horizontal 15 shaft having fixed thereon a cam below the orbit of the spindles, a mutilated pinion to mesh with the gear that is fixed upon the vertical shaft of the carrier frame, a plunger above said cam and below the orbit of said 20 spindles, a lock for said spindles adapted to engage and lock successively the spindles after 25

each intermittent movement of the carrier frame, a vertical shaft above the orbit of the can carrier disks, a gripping disk upon the lower end of said vertical shaft, an irregular cone upon the vertical shaft above the orbit of the can carrier disks, a cross-bar fixed upon the same vertical shaft, double swing levers pivoted to said cross-bar, seaming disks carried by the double swing levers, a vertical shaft having fixed thereon a cam having a series of steps and inclines, driving connection between the horizontal shaft and the vertical shaft having fixed thereon a cam with inclines and steps, and intermediate connection between the cam having a series of steps and inclines and the irregular cone whereby the irregular cone is lowered and raised by the rotation of said cam, substantially as illustrated and described. 30 35 40 45

In testimony whereof I affix my signature, in the presence of two witnesses, this 29th day of November, 1893.

JOHN W. ROBERTS.
